UNITED STATES PATENT OFFICE.

THOMAS H. BUCKLEY, OF WORCESTER, MASSACHUSETTS.

DESIGN FOR A LUNCH-WAGON BODY.

SPECIFICATION forming part of Design No. 22,743, dated August 22, 1893.

Application filed June 22, 1893. Serial No. 478,520. Term of patent 7 years.

To all whom it may concern:

- Be it known that I, THOMAS H. BUCKLEY, a citizen of the United States, residing at Worcester, in the county of Worcester and State of Massachusetts, have invented and produced a new and original Design for a Lunch-Wagon Body, of which the following is a specification, reference being had to the accompanying drawings, forming a part thereof.
- 10 My invention consists in my new and original design for a lunch wagon body, as will be hereinafter fully described.
- Referring to the drawings:—Figure 1 is a perspective front end view of a lunch wagon body, showing my design, looking in the direction of arrow *a*, Fig. 2, and Fig. 2 is a perspective rear end view of a wagon body, showing my design, looking in the direction of arrow *b*, Fig. 1.
- 15 In my design for a lunch wagon body, a row of windows extends entirely around the wagon body at the top portion thereof, just below the roof, except where there is a door in each side of the wagon body.
- 20 In the accompanying drawings, 1 is a wagon body of my design, which has a door 2 in each side thereof, and double casement windows 3 in each end thereof and in each side thereof at the front portion of the wagon body, and
- 25 also the long windows 4 on each side of the wagon body at the rear portion thereof; said windows extend down from the top to about half the height of the wagon body, in the ordinary way. A series of windows 5, interposed between the doors 2 and windows 3 and
- 30 4, extends entirely around the wagon body at

the upper portion thereof, and just below the roof 6, and form in connection with the doors 2 and windows 3 and 4, the upper portion of the wagon body. By means of the series of 40 windows 5 extending around the top of the wagon body, in connection with the doors 2 and windows 3 and 4, the solid portion of the sides and ends of the wagon body is broken in a horizontal plane, and does not extend the 45 full height of the wagon body at any point thereof. The row of windows 5 in the upper portion of the wagon body gives a light and airy appearance to the wagon body; said windows may be made of colored or figured glass 50 to add to the attractive appearance of the wagon, and at the same time allow the interior to be lighted from exterior artificial light.

The advantages of my design for a lunch wagon body, over the design for lunch wagon bodies prior to my invention, will be readily appreciated by those skilled in the art, and the leading feature of my design consists in a series of windows which in connection with the doors and windows in the ordinary design 55 of lunch wagon bodies, extends entirely around the top portion of the lunch wagon body, so as to leave only the lower part thereof of the solid portion which forms the solid frame of the lunch wagon body. 65

What I claim is—

The design for a lunch wagon body, substantially as shown and described.

THOMAS H. BUCKLEY.
